UNITED STATES PATENT OFFICE

HYMEN GOLDBERG AND HARRY GOLDBERG, OF SCHENECTADY, NEW YORK

SEPARABLE BUTTON

Application filed February 18, 1932. Serial No. 593,901.

This invention relates to improvements in buttons, and more particularly to separable buttons requiring no thread or the like to attach them.

5 An object is to provide such a button having attaching means presenting faces sufficiently ample in area to hold a button against tearing from the cloth or the material to which it is attached.

10 Another object is to provide attaching means for such a button which will present to the surface of the cloth or the material about the button hole a rounded surface not apt to wear or tear the material or the threads or similar material used in working the button hole.

Another object is to provide such a button with attaching means which press into both sides of the cloth or other material to which it is attached and prevents that portion of the separable button passing through the hole formed in the material from working the hole larger.

Still another object is to provide a separable button which is easy to attach to or detach from the cloth or other material with which it is associated and which includes a button portion which is readily attached to or detached from the remainder of the separable button so that buttons having different designs or insignia on their faces may be readily substituted for the button portion removed and yet utilizing the remainder of the separable button.

35 Another object is to provide a separable button in which the button itself is free to swing about, as is desirable in buttoning and unbuttoning garments.

Still another object is to provide a separable button which may be attached and detached with ease by persons acquainted with the method but cannot be readily detached by unauthorized persons or work loose of its own accord.

45 Other objects and advantages of this invention will be apparent during the course of the following detailed description taken in connection with the accompanying drawings, forming a part of this specification and in which drawings:—

Figure 1 is a view partly in vertical section as the preferred form of the separable button.

Figure 2 is a view substantially on the line 2—2 of Figure 1.

Figure 3 is a top plan view of an outwardly facing base plate employed in the assembly of the separable button shown in Figures 1 and 2.

Figure 4 is a top plan view of a complementary or inwardly facing base plate and skirted washer employed in the assembly of the separable button shown in Figures 1 and 2.

Figure 5 is a top plan view of a washer associated with the outwardly facing base plate and shown carrying a shank provided with a hook.

Figure 6 is a tool or device employed in attaching the separable button shown in Figures 1, 2 and 7.

Figure 7 is a view partly in vertical section of a modified form of separable button.

Figure 8 is a bottom plan view of the type of outwardly facing base plate employed in the assembly of this modified form.

Figure 9 is a top plan view of a complementary or inwardly facing base plate and skirted washer employed in the assembly of the preferred and of this modified form.

Figure 10 is a perspective view of an anchor forming part of this modified form of separable button.

Figure 11 is a view partly in vertical section of a second modified form of the separable button.

Figure 12 is a plan view looking upon the modified form shown in Figure 11 from the inner side of the material to which it is attached, illustrating how a lever employed in the construction may be canted in order to lock or unlock the same.

Figure 13 is a view similar to Figure 12 showing the lever locked into place.

Figure 14 is a vertical section view through an inwardly facing base plate employed in this second modified form, with a device for locking together the several parts of the separable button.

Figure 15 is a side elevation of the inward-

100

ly facing base plate, with the lever shown in Figures 11 and 13 locked into place.

Figure 16 is a view on the line 16—16 of Figure 13.

5 Figure 17 is a view of a blank forming the lever shown in Figures 12 and 13.

Figure 18 is a view of a blank forming a locking tongue or detent employed in the device mentioned in connection with Figure 10 14.

In the drawings, wherein for the purpose of illustration is shown both preferred and modified forms of the invention, the letter A designates generally the preferred form of 15 separable button shown in Figures 1 to 5, which includes a conventional button member B and coupling means C for securing the button member to a portion of material D, a tool E being provided to assist in the coupling and uncoupling of the several parts of the member B.

The separable button A may be such as is affixed to uniforms and the like.

25 The button member B includes a head or button proper 20 and a shank 21 provided with an eye 22 and is of conventional construction.

30 As for the coupling means C, this includes a pair of axially aligning outer and inner base plates 25 and 26. The outer base plate 25 is next to or faces the under surface of the head 20 and its outer or button facing surface 27 is preferably convex while the opposite or material facing surface 28 is preferably flat and its edge defines a circle. An annular recess 29 extends into the body of the base plate 25 from the surface 28 and from this recess an axial opening 30 continues to the surface 27. Extending radially from the 35 opening 30 is a slot or way 31 which is preferably slightly smaller in width than the circumference of the opening 30 and the slot ends short of the edge of the base plate or at the wall of the recess 29 as shown in Figure 1. On either side of the slot 31 is a 40 groove 32 which is curved to accommodate the curved lower end of the shank 21 as shown in Figure 2. A washer 33 is accommodated in the recess 29 and is provided with an axial 45 screw threaded opening 34 which of course aligns with the opening 30. The height of the washer 33 is such that its outer face will be flush with the surface 28 of the base plate. A pair of slots 34 cut into the periphery of 50 the washer are provided to permit the insertion of a tool (later described) to manipulate the washer.

55 The opposite or inner base plate 26 preferably includes two parts,—a base plate proper 35 and a skirted washer 36. The base plate proper has preferably an outer convex surface 27 while the inner or material facing surface 38 is stepped so that a central flange 39 is provided at the base of which is a surface 40 paralleling the top of the flange and

extending to the edge of the base plate proper. Through the base plate extends an axial opening 41 provided with a plurality of projections 42 such as are formed by screw threads. About the flange 39 is the washer 36 having a depending skirt portion 44 of light weight metal adapted to be bent over the convex surface of the base plate proper, as shown in Figures 1 and 2. It will be noted that when in place as shown in these figures, the circumference of the inner face of the assembled parts 35 and 36 is substantially equal to the face 28, that the height of the washer 36 is slightly more than the height of the flange 39 and that the skirt portion 44 does not cover the whole convex surface of the base plate proper. A pair of sockets 45 in the convex surface are provided for a purpose later described.

55 A shank member 50 preferably shaped like an inverted J is provided, with its shank portion 51 provided with a plurality of spaced apart recesses 52 such as would be produced by screw threads. This shank is adapted to detachably carry the two base plates 25 and 26. The crook or offset portion 53 of the shank member 50 may be reduced in diameter over the shank portion 51. The crook portion 53 is accommodated within the opening 30 and slot or way 31 so that a hook may be formed as shown in Figure 1. When the crook portion is inserted in the eye 21 of the shank 20 and the latter drawn towards the base plate 25 until the curved portion of the shank 20 fits into the groove 32 the button member B cannot become detached from the coupling means C. The several parts making up the coupling means may be of brass or steel or of any similar suitable material.

90 The material D to which the separable button may be attached may comprise cloth, leather, rubber or similar material folded upon itself or not folded.

95 The tool E illustrated in Figure 6 is provided for assisting in coupling and uncoupling the several parts of the means C as well as punching the necessary holes in the material D to accommodate the shanks. It includes a tapered shank portion 60 terminating at one end in a point 61 and provided at its opposite end with a pair of resilient legs 62 normally spaced apart a distance sufficient so that their extremities 63 may be easily inserted into the slots 34 and sockets 45 for the purpose of assisting in rotating the screw threaded washer 33 and the base plate 26. The pointed and tapering shank 60 may be employed by the user to punch the holes in the material to accommodate the shanks of the several coupling means provided.

100 In coupling the button member B to the material D, after the hole mentioned has been punched in the material, the shank member 50 with the crook end or portion 53 foremost is inserted into the opening 30 and slot 31

of the base plate 25 and the crook end then inserted in the eye 22 of the shank 21 of the button member. The screw threaded washer 33 is now rotated by means of the tool E 5 along the screw threaded shank of the shank member 50 until the curved portion of the shank 21 is in the groove 32 and the extremity of the crook portion 53 is within the slot as shown in Figure 1. The shank is now inserted into the hole formed in the material 10 and into the hole in the washer 36, the skirt portion of which may or may not have been pressed about the convex surface of the base plate proper 35. The latter is then rotated 15 on the shank 51 by means of the tool and sockets 45 until it has pressed the washer tight against the material. The skirt may then be pressed over the convex surface of the base plate proper. In removing the separable button, as for instance, in pressing the garment to which it is attached, replacing the button member with one of a different design or the like, or removing the separable button from a discarded garment, the base 20 member 26 is rotated off the shank 51 and the shank withdrawn from the material. The button proper can be removed, as is apparent, by rotating the washer 33 off the shank 51 and moving the confining crook 25 portion away from the base plate 26 until the button proper can be removed.

As for the separable button F disclosed in Figures 7 to 10 inclusive, the same includes a button member G and a coupling means H 35 for securing the button member to a portion of material D.

The separable buttons F may be such as are affixed to uniforms as utilitarian buttons, as decorations or trimmings, as buttons on sleeves, lapels and collars.

This button, when serving merely as a trimming or to denote rank or the like will not swing about on a pivot (as is generally desirable in buttons used primarily for buttoning, but not generally desirable in buttons on the lapel, collar or sleeve).

The button member G includes a head or button proper 70 which may be shaped like the button proper 20 but is provided with a 50 straight shank 71 circular in cross section, which has a plurality of recesses 72 in its peripheral surface, similar to those formed by conventional screw threads. This shank is provided with a radially extending groove 73 throughout its length.

As for the coupling means H, this includes a pair of axially aligning outer and inner base plates 75 and 76. The outer base plate 75 is next to or adjacent the under side 60 of the head 70 and its outer surface 77 is preferably convex while the opposite or material facing surface 78 is preferably flat and its edge defines a circle. A groove or way 79 extends from adjacent this edge towards the 65 axis of the plate where it joins an axially

positioned screw threaded opening 80 through the plate. A groove or way 81 extends along this opening as shown in Figure 7 and joins the groove 79. Preferably at the edge of the surface 78 depends a prong 82 adapted to sink into the material to which the separable button is secured.

The opposite or inner base plate 76 is similar in every detail to the base plate 26 and the parts thereof have been numbered to correspond to similar parts of the base plate 26.

An L-shaped anchor 85 is provided, in conjunction with the shank 71, and forming an offset portion thereof, with its longer leg 86 disposed in the groove or way 73 and the shorter leg 87 in the groove or way 79. Preferably at the free end of the shorter leg 87 is a depending prong 88 which sinks into the material to which the separable button is affixed. Thus it will be seen that this anchor 85 serves both to space the button head from the base plate and also to prevent the button and base plate 75 from turning, since the prong sinks into the material and anchors the parts. Like the coupling means C, the coupling means H may be of brass, steel or the like.

It is apparent that after the necessary hole is punched in the material D, the base plate 75 is rotated upon the shank 71 until the grooves 73 and 79 align and the base plate has taken a position on the shank sufficient to permit the insertion of the longer leg of the anchor into the groove 75 and the shorter leg into the groove 79, with the shorter leg flush with the surface 78 as shown in Figure 7. The shank is then inserted into the material and the base plate 78 is threaded upon the shank as heretofore brought out with respect to the base plate 26. Both of the prongs will then be firmly inserted in the material.

Now as to the separable button J disclosed in Figures 11 to 18, this includes a button member K and coupling means L for securing the button member to a portion of the material D.

The separable button J may be such as is attached to uniforms and the like and permits the button member to swivel so that it may be more easily manipulated in buttoning and unbuttoning.

The button member K is similar to the button member B and similar reference characters designate corresponding parts to both K and B.

With respect to the coupling means L, the same includes a pair of axially aligning outer and inner base plates 95 and 96. The outer base plate 95 is similar to the outer base plate 25 except that it is preferred that no recess, similar to the recess 29 be provided, and similar reference characters will be used to designate corresponding parts of both base plates 95 and 25. In other words, the two base plates are the same except that the mate-

rial facing surface 28 of the base plate 95 is unbroken except for the opening 30. The inner base plate 96 includes a body portion 97 provided with an axial opening 98, a comparatively deep recess 99 in the outer face 100 of the base plate, having a cam surface 101 at the base of the recess, and a shallow recess 102 extending from the recess 100 towards the edge of the body portion. 10 This shallow recess has one preferably inwardly beveled side wall 103 and one preferably inwardly curved opposite side wall 104 both walls terminating in facing flanges 105 and 106 level with the face 100. From the outer edge of the recess 102 the body portion is notched or grooved to its outer edge as at 107 to provide a space for the insertion of the tip of the finger or of the thumb as shown in Figure 12. At opposite sides of the recess 99 15 the material forming the body portion is removed as by slitting the material as shown at 108 in Figures 12 and 13 forming tongues which are bent outwardly and material removed to form bearings 109. A preferably 20 polygonal pivot pin 110 having cylindrical ends 111 is inserted into the recess, bridging it, with the ends 111 in the bearings 109 whereupon the tongues mentioned are depressed level with the face 100 holding the 25 ends 111 in the bearings but allowing some slight play, so that the pivot pin may be slightly tilted.

A lever 112 shown in Figure 17 as a blank, may be suitably secured to the pivot pin as 30 by bending its arms 113 about the pivot pin with the free end 114 of the lever projecting towards the edge of the body portion and terminating in a finger grip 115. From Figure 15 it will be seen that this lever end 114 35 can be accommodated between the two side walls 103 and 104 and under the flanges 105 and 106 and Figure 12 illustrates how, by canting the lever and associated structure, this can be done, since one edge of the lever 40 will slide down the beveled surface and permit the opposite edge to be snapped into place below the flange 106.

Projecting from the opposite side of the pivot pin 110 and in the opposite direction 45 from the lever is a tongue or detent 116, a blank of which is shown in Figure 18. This tongue is provided with projections 117 for the purpose of securing it loosely to the pivot pin which is provided with sockets 119 to receive these projections. These sockets have 50 one straight wall and one inclined wall 120 as shown in Figures 11 and 14. The tongue 116 above or beyond the projections 117 is provided with a shallow socket 121 while its 55 free end is concaved as at 122. The surface 101 is indented by a shallow socket 123 and into these sockets 121 and 123 is inserted the 60 opposite end of a leaf spring 124 which normally urges the detent 116 toward the opening 98 and the projections 117 away from

the inclined wall 120 of the sockets 119 as well as retains the projections in the sockets.

A shank member 130 preferably shaped like an inverted J is provided, with its shank portion 131 having a plurality of spaced apart recesses 132 provided between adjacent spaced apart flanges 133 with inwardly beveled faces as shown at 134. This shank is adapted to detachably carry the two base plates 95 and 96. The crook or offset portion 135 of the shank member may be slightly reduced in circumference over the shank portion 131. This crook portion is accommodated within the opening 30 and slot 31 so that a hook may be formed, shown in Figure 11. When the crook portion 135 is inserted into the eye 21 of the shank 20 and the latter drawn towards the base plate 95 until the curved portion of the shank 20 fits into the grooves in the base plate 95 similar to the grooves 32, the button member K cannot become detached from the coupling means L. The end of the crook or offset portion 135 is pointed as at 136 and since there is no washer in the way, this point sinks into the material D and prevents rotation of the several parts. The coupling means L may be of any approved material such as bronze, copper, steel or the like.

In attaching the separable button K to the material D, after the necessary hole is punched in the material D, the shank member is inserted, crook end foremost, into the opening 30 and slot or way 31, the crook end inserted in the eye of the button member, and the shank member 130 and then drawn in the opposite direction so that the curved portion of the shank of the button member will enter the grooves mentioned and the pointed end of the shank member will enter the material when the shank portion 130 is inserted in the material and the outer base plate pressed against the material. The inner base plate is now secured to the shank portion 131 and since the walls 120 of the sockets 119 are inclined, the tongue or detent 116 may rock, and permit its free concaved end to slide up the beveled faces of the flanges 133. When the inner base plate is tight against the material, the tongue will be in one of the several recesses 132 urged there by the spring 124 and held there by the lever, the end of which is detachably carried under the flanges 105 and 106.

In removing the separable button last described, the lever 112 is canted and slipped out from under the flanges 105 and 106 thus releasing the detent or tongue from the recess in which it is projected, the tongue riding over the cam surface, and the base plate 96 may then be removed. The shank member 130 is then slipped from the base plate 95 and the button member may be removed.

Changes in detail may be made to the forms of invention herein shown and described,

without departing from the spirit of the invention or the scope of the claims.

What is claimed is:

1. In a separable button, a button member, 5 a pair of base plates, each of said base plates having a substantially axially extending opening and a material contacting face, and one of said base plates provided with a way in a face thereof, a shank carrying said button member and extending into the openings in the base plates, said shank provided with an offset portion projecting into said way, and means detachably securing said shank to one of said base plates.
- 15 2. In a separable button, a button member, a pair of base plates, each of said base plates having a substantially axially extending opening, one of said base plates provided with a projection extending radially into said opening therein and the other base plate having a way extending radially from said opening, and a shank carrying said button member and extending into said opening, said shank provided with a plurality of radially extending recesses in its peripheral face, any selected recess receiving said projection, said shank also provided with an offset portion extending into said way.
- 20 3. In a separable button, a button member, an outer base plate having a face facing said button member; an inner base plate comprising a main body portion having a face confronting the material to which said separable button is attached and also provided with an annular flange projecting from said face and a washer surrounding and in contact with said flange, having a face pressed into the material to which said separable button is attached, said washer also provided 25 with a skirt portion extending over the opposite face of said last mentioned plate and in contact therewith, both of said base plates provided with axially extending openings therethrough; a shank carrying said button member and extending into the openings in said base plates, means detachably securing said shank to one of said base plates and means detachably securing the shank to the other of said base plates.
- 30 4. In a swivelled separable button, a button member provided with an eye portion; an outer base plate having a face facing said button member and provided with an axially extending opening and a slot communicating therewith; an inner base plate facing the outer base plate provided with an axially extending opening; a J-shaped shank member having a shank portion disposed in said openings and a hook portion disposed through 35 said eye portion and the free end of the hook portion in said slot; means detachably securing said shank to one of said base plates; and means detachably securing the shank to the other of said base plates.
- 40 5. In a swivelled separable button, a button member provided with an eye portion; a base plate having a face facing said button member and provided with an axially extending slot communicating therewith and also provided with an annular recess in the opposite face; a washer disposed in said recess, said washer having a screw threaded opening aligning with the first mentioned opening; a second base plate facing said first mentioned base plate, provided with an axially 45 extending screw threaded opening, and a J-shaped shank member having a shank portion screw threaded and in engagement with the screw threaded opening of said washer and the second mentioned base plate and a hook portion through said eye portion with the free end of the hook portion in said slot.
- 45 6. In a swivelled separable button, a button member provided with an eye portion; a base plate having a face facing said button member and provided with an axially extending slot communicating therewith, and also provided with an annular recess in the opposite face; a washer disposed in said recess, said washer having a screw 50 threaded opening aligning with the first mentioned opening; a second base plate facing said first mentioned base plate, provided with an axially extending screw threaded opening, and a J-shaped shank member having a shank portion screw threaded and in engagement with the screw threaded opening of said washer and the second mentioned base plate and a hook portion through said eye portion with the free end of the hook portion in said slot.
- 55 7. In a swivelled separable button, a button member provided with an eye portion, an outer base plate having a face facing said button member and provided with an axially extending opening and a slot communicating therewith and also provided with an annular recess in the opposite face; a washer disposed in said recess, said washer having a screw 60 threaded opening aligning with the first mentioned opening; an inner base plate including a body member having a face facing said first mentioned base plate provided with a depending skirt portion extending over the outer face of said second body member; and a screw threaded J-shaped shank member carrying said base plates having its shank portion in screw threaded engagement with the screw threaded opening in said first mentioned washer and the screw threaded opening in said second mentioned base plate and its hook portion through said eye portion with the free extremity thereof in said slot.
- 65 8. In a swivelled separable button, a button member provided with an eye portion; an 65

outer base plate having a face facing said button member and provided with an axially extending opening and a slot communicating therewith and also provided with an annular 5 recess in the opposite face; a washer disposed in said recess, said washer having a screw threaded opening aligning with the first mentioned opening; an inner base plate including a body member having a face facing said first 10 mentioned base plate provided with a screw threaded axially extending opening therethrough and an annular flange extending from said face about said opening and a washer about said flange provided with a 15 depending skirt portion extending over the outer face of said body member, with the free ends of said skirt portion short of the central portion of said face; and a screw threaded J-shaped shank member carrying said base 20 plates having its shank portion in screw threaded engagement with the screw threaded opening in said first mentioned washer and the screw threaded opening in said second mentioned base plate and its hook portion 25 through said eye portion with the free extremity thereof in said slot; said outer face of the body member provided with recesses extending into the base plate whereby a tool may be inserted in said recesses to rotate the 30 last mentioned base plate upon the screw threads of said shank.

9. In a separable button, a button member provided with an elongate substantially straight screw threaded shank, said shank 35 having a radially extending longitudinal groove, a pair of opposed base plates detachably secured to said shank, said base plates provided with aligning axially extending screw threaded openings receiving said 40 shank, and one of said base plates provided with a groove extending along its screw threaded opening, and with a radially extending groove in its face, said radially extending groove extending to said first mentioned groove, and an L-shaped anchor disposed in said grooves.

10. In a separable button, a button member provided with a substantially straight screw threaded shank, said shank having a radially 50 extending longitudinal groove, a pair of opposed base plates detachably secured to said shank, said base plates provided with aligning axially extending screw threaded openings receiving said shank, and one of said 55 base plates provided with a groove extending along its screw threaded opening, and with a radial groove in its face, said last mentioned groove extending to said first mentioned groove, and an L-shaped anchor provided with a prong depending from a shorter leg thereof, with the longer leg of said anchor disposed in said other groove, and said prong projecting towards the opposed base plate.

11. In a separable button, a button member 60 provided with a screw threaded shank, said

shank having a radially extending groove throughout its length, an outer base plate detachably secured to said shank and provided with a prong depending from the base thereof, an inner base plate detachably secured to said shank confronting said first mentioned base plate, both of said base plates provided with aligning axially extending screw threaded openings receiving said shank and one of said base plates provided with a groove extending along its screw threaded opening, and with a radially extending groove in the base thereof, said last mentioned groove leading to the other groove and an L-shaped anchor provided with a prong depending from the shorter leg, with the longer leg of said anchor disposed in said first named groove and the shorter leg disposed in said other groove, and said prongs projecting towards the confronting base plate.

12. In a swivelled separable button, a button member provided with an eye portion, an outer base plate having a face facing said button member and provided with an axially extending opening and a slot communicating therewith, an inner base plate facing the outer base plate and provided with an axially extending opening, a J-shaped shank member having its shank portion disposed in said opening and its crook portion through said eye portion and the free end of the crook portion in said slot, said free end having a pointed extremity extending below the base of the first mentioned base plate; and means detachably securing the inner base plate to the shank.

13. In a separable button, a button member, a shank secured thereto, said shank provided with a pair of spaced apart peripheral flanges, and a base plate provided with an axially extending opening accommodating said shank and with a recess communicating therewith, said recess having a cam surface, said base plate also provided with a retractable tongue normally extending into the space between said pair of flanges and into said recess, detachably securing said base plate to said shank and movable over said cam surface when retracted.

14. In a separable button, a button member, a shank secured thereto, said shank provided with a pair of spaced apart peripheral flanges, and a base plate provided with an axial opening accommodating said shank and also provided with a recess having a cam surface extending to said opening and a flanged portion, said base plate also provided with a pivot pin in said recess having a socket carrying an L-shaped detent normally disposed between said flanges with a leg of said detent loosely accommodated in said recess and a manipulating lever operatively connected to said detent and held against leverage in said flanged portion of said base plate, whereby the free end of said detent will

travel over said cam surface upon retraction of said detent by said lever.

15. In a separable button, a button member, a shank secured thereto, said shank provided with a plurality of spaced apart peripheral flanges having beveled faces, and a base plate provided with an axially extending opening accommodating said shank and having a recess extending to said opening, a portion of said recess being flanged and said base plate also provided with a pivot pin pivoted in said recess having a V-shaped socket with a substantially L-shaped detent accommodated in said recess and loosely secured 10 to said pivot pin by a leg of said detent in said socket, the free end of said detent adapted to slide up said beveled faces, said base plate also provided with a manipulating lever operatively connected to said detent and 15 normally held against leverage in said flanged portion of said recess.
